UNITED STATES PATENT OFFICE.

FRED EVANS, OF SUMMIT, NEW JERSEY, ASSIGNOR TO LOUIS V. ARONSON, OF NEWARK, NEW JERSEY.

FLASH LIGHT.

1,411,614.

Specification of Letters Patent. Patented Apr. 4, 1922.

Application filed March 22, 1920. Serial No. 367,927.

To all whom it may concern:

Be it known that I, FRED EVANS, a citizen of the United States, residing in the city of Summit, in the county of Union and State 5 of New Jersey, have invented certain new and useful Improvements in Flash Lights, of which the following is a full, clear, and exact description.

This invention relates to flash-lamps and 10 casings therefor, and aims to provide improvements therein.

An object of the invention is to provide from pressed metal a tapering casing, made up of longitudinally separable sections, and 15 provided with co-operating means whereby to be snapped together; one of the sections being provided with spaced-apart studs, and the other with corresponding slots receptive of said studs.

20 A further object is the provision of a casing, specifically designed to maintain without any separate securing means, a skeleton frame, arranged to carry, as a unitary structure, the interior working parts.

25 The present invention consists in the general and specific construction and combination of parts as hereinafter described, and it is defined in the appended claims.

In the drawing, forming a part of this 30 specification, Figure 1 represents a central longitudinal sectional view of a flash-lamp embodying the present features of improvement.

Fig. 2 is an elevational view with the front 35 casing section removed, exhibiting the interior, parts being shown in section.

Fig. 3 is a cross-section, taken on the line 3-3 of Fig. 2.

Referring to the drawing, and particularly 40 to Figs. 2 and 3, it will be observed that the casing, as an entirety, comprises an elongated figure having opposing flat sides and opposing tapering sides.

More specifically, the casing comprises a 45 rear section 4, formed with opposing tapering sides 5; and a front section 6, similarly formed with tapering sides 7, designed to engage snugly over the sides 5 for a distance. As a means of securing the sections together with a snap action, the sides 5, on 50 their marginal edges, are provided with spaced-part studs 8; and in correspondence therewith, the sides 7 are provided with slots 9 receptive of said studs; it being observed 55 that the edges of the sides 7 are turned

slightly outward as shown at 10, in order readily to snap these parts together and as readily to separate them when desired. At the larger end of the casing, the tapering sides are made with an inwardly curved region as at 11, terminating in a flattened extremity 12, for a purpose that will later appear. These sections are produced from thin pressed metal, such as sheet iron, sheet aluminum or the like. At the smaller end of the 60 casing, the defining sides are bent upon themselves to form together a recessed ring 13, in which is engaged the flanged rim of a reflector 14, formed with a central inwardly projecting socket 15. Also engaged in the 65 ring 13 and against the reflector rim, is a lens 16; these parts being held fixedly in position by bending over upon the lens the outer edge 17 of the ring.

Provision is made for supporting the 70 remaining parts, as a unitary structure, upon a skeleton frame of rectangular form, and consisting of the side plates 18 and 19, connected by the top and bottom plates 20 and 21, respectively. Adjacent the bottom plate 75 21, the sides are formed with outwardly projecting lugs 22, designed as guides to engage the casing and to hold the skeleton frame centrally therein.

Upon the top plate 20, there is secured a 80 plate of non-conducting material 23, formed with branches as shown in Fig. 3, to engage the sides of the casing and thereby to maintain the top portion of the frame in the desired central position. Engaged between 85 the side plates 18 and 19 are the arbors 24, 25 and 26. The arbor 24 projects through the plate 19 to receive a pinion 27, with which is engaged a rack-bar 28, longitudinally slotted at 29 to receive the guiding 90 studs 30, which project from the plate 19. This rack-bar 28 merges into a rod 31, which extends through a guiding lug 22, and also through the flat casing end 12, to receive the exterior ring 32. Secured on the rod 31 95 100 is a collar 33; and coiled around this rod is a compression spring 34, which is confined between said collar and the adjacent guide 22. This arrangement is such that each time, by means of the ring 22, the rod is 105 drawn outwardly, the spring 34 will act to re-position it.

Pinned on the arbor 24 is a gear wheel 35, in mesh with a pinion 36, fast with a gear wheel 37 on the arbor 25. The gear wheel 110

37 imparts its movement to a pinion 38, fast with a ratchet wheel 39 on the arbor 26. Loosely mounted on the arbor 26 is a permanent magnet 40, formed with a plurality 5 of branches 41, designed to spin around an equal number of armatures 42, coil wound in series, and attached to a guard sleeve 43, which surrounds the arbor 26 and which is fixedly secured to the plate 18. Pivoted at 10 44 to a magnet branch is a pawl 45, which is normally held in engagement with the ratchet teeth by means of a spring 46, pinned at 47 to a magnet branch.

Whenever, by means of this construction, 15 the rod 31 is drawn downward by a quick movement, the magnet will be spun about the armature, setting up an electric current; and each time the rod is drawn in, under the influence of the spring 34, the 20 gear train will be actuated reversely, but the magnet will not be actuated, since the pawl rises out of the ratchet teeth.

One end 46 of the armature winding proceeds to a conducting spring 48, with which 25 it is secured by a binding-post 47 upon the insulating material 23. The conducting spring 48 is arranged to engage a terminal of the incandescent lamp 49, which is screw-threaded into the socket 15. The other end 30 50 of the armature winding is grounded at 51 on the skeleton frame, the return to the point 51 being accomplished through the lamp base, the reflector and the casing parts.

Having thus described my invention, what 35 I claim is:—

1. In a pocket flash-lamp, the combination with a metallic elongated casing consisting of separable complementary sections flanged one intimately upon the other and 40 the opposing flanges tapering toward one end, the smaller end of the casing terminating in a ring opening and an opening provided in the larger end, of a reflector carrying an incandescent lamp secured in 45 said ring opening, a longitudinal skeleton frame disposed in said casing and having guides for holding it in position therein, a current-generator carried by said frame and connected in circuit with said lamp, mechanism carried entirely by said frame for actuating said generator and including a pin- 50

ion, a rack-bar slidably maintained on said frame in engagement with said pinion and merging into a rod having extension outwardly through the opening of the larger 55 end, and means combined with said rod for holding the rack-bar normally in operative position.

2. In a pocket flash-lamp and in combination, a metallic elongated casing consisting 60 of separable complementary sections forming a ring opening at one end, said sections being flanged one intimately upon the other and the opposing flanges tapering toward said opening, means on the overlapping 65 flanges for securing them together and consisting of co-operating studs and slots, the larger end of the casing being provided with an opening, a reflector secured in said ring opening and carrying an incandescent 70 lamp, a longitudinal skeleton frame disposed in the casing and carrying a current-generator connected in circuit with said lamp, mechanism carried entirely on said frame for actuating said generator and including a pinion, a rack-bar slidably held on 75 said frame in engagement with said pinion and having a handle portion extending outwardly through the opening of the larger casing end, and a spring acting on said rack-bar for holding it normally in operative position.

3. A pocket flash-lamp casing made of sheet metal and consisting of elongated separable complementary sections forming a reflector receiving opening at one end, said sections being flanged one intimately upon the other and the opposing flanges tapering toward said opening, the said flanges at the larger end curving sharply inwardly to 90 form a flat extremity at the larger end and having an operating rod receiving opening therein, and provision for detachably connecting the overlapping flanges consisting of studs on one flange and corresponding 95 slots cut in the confronting flange.

This specification signed and witnessed this eighth day of March, 1920.

FRED EVANS.
